DESIGN FOR A HANDKERCHIEF CONTAINER

Elmer P. Goldsmith, New York, N. Y.

Application August 19, 1936, Serial No. 64,479

Term of patent 3½ years

To all whom it may concern:

Be it known that I, Elmer P. Goldsmith, a citizen of the United States of America, residing in Manhattan county of New York, and State of New York, have invented a new original, and ornamental Design for a Handkerchief Container, of which the following is a specification, reference being had to the accompanying drawing, forming part thereof, wherein,

The figure is a front view of a handkerchief container showing my new design.

The rear view of the handkerchief container

shown in the figure is identical to the front portion of the handkerchief container, save for the omission of the slit opening.

The container is substantially round in contour and the side views present the same appearance as the front view, except for the omission of the opening member.

I claim:

The ornamental design for a handkerchief container, substantially as shown, and described.

ELMER P. GOLDSMITH.
